UNITED STATES PATENT OFFICE.

CHARLES W. EVERSON, OF ORANGE, NEW JERSEY.

DESIGN FOR A FRAMEWORK OR HEAD OF A PRINTING-WHEEL HAND-STAMP.

46,276.

Specification for Design.

Patented Aug. 18, 1914.

Application filed December 20, 1913. Serial No. 808,045. Term of patent 7 years.

To all whom it may concern:

Be it known that I, CHARLES W. EVERSON, a citizen of the United States, and residing at Orange, in the county of Essex, State of New Jersey, have invented a new, original, and ornamental Design for the Framework or Head of a Printing-Wheel Hand-Stamp, and of which the following is a specification, reference being had to the accompanying drawing, forming part thereof.

Figure 1 of the accompanying drawing

is a side view of my newly designed framework or head for a printing wheel hand stamp, and; Fig. 2 a top plan view thereof.

I claim:

The ornamental design for the framework or head of a printing wheel hand stamp, as shown.

CHARLES W. EVERSON.
